UNITED STATES PATENT OFFICE

PHILIP B. SADTLER, OF CHICAGO, ILLINOIS, ASSIGNOR TO SWENSON EVAPORATOR COMPANY, OF HARVEY, ILLINOIS, A CORPORATION OF ILLINOIS

PROCESS OF EVAPORATION

Original application filed July 9, 1926, Serial No. 121,452. Divided and this application filed August 6, 1927. Serial No. 211,014.

My invention relates to methods or processes of evaporation.

It will be explained in conjunction with and particular reference to evaporating apparatus of the so-called "vertical tube" type wherein the liquid to be evaporated circulates upwardly through vertical tubes while the heating medium is applied to the outside of the tubes.

10 This application is a division of my pending application Serial No. 121,452; filed July 9, 1926.

Heretofore it has been the common practice to provide tubes of relatively large diameter and short length or in coils or with abrupt bends and depend upon a relatively slow movement of the liquid into and through the same. Ordinarily natural circulation, that is, the circulation induced by the lifting 20 effect of bubbles of vapor rising through the tubes has been depended upon to effect the heat transfer from the tubes to and through the liquid. Of course, the agitation and circulation of the liquid under such conditions 25 is relatively sluggish, the transfer of heat is correspondingly slow and evaporation proceeds at a comparatively low rate.

The so-called "film" theory of heat transfer to and from metallic surfaces is now generally accepted. According to this theory the principal resistance to heat transfer from the heating medium, such for example as steam, on the outside of the evaporator tubes to the tubes and from the inside surfaces of the 35 tubes to the liquid within them is due to relatively stagnant films of fluid lying against the outside and inside walls of the tubes. The film on the inside of the tubes is composed of the liquid being heated. The film on the outside 40 of the tubes is composed, for example, of condensed steam and air and other non-condensable gases, and is usually called the steam film. These films produce most of the temperature drop between the heating fluid, for 45 example, steam, and the liquid being evaporated. Thus, ignoring the effects of the metal walls of the tubes, and of scale which may be present, the overall rate of heat transfer from steam on the outside of the tubes to 50 the liquid on the inside of the tubes may be

represented by the following formula, where-in U is the overall rate of heat transfer, K_1 is the steam film coefficient, and K_2 is the liquid film coefficient:

$$U = \frac{1}{1/K_1 + 1/K_2} \quad 55$$

It has been recognized that increasing the velocity of the liquid flowing through the evaporator tubes would decrease the thickness of the stagnant liquid film and correspondingly raise the liquid film coefficient with the result that the rate of heat transfer is increased. Some attempts have been made to augment the velocity of the circulating 60 liquid by indirect methods such as the provision of screw conveyors and paddle or propeller wheels and the introduction of buoyant agents such as air or other gases. Where 65 viscous or easily scaling liquids have been treated, forced circulation has been provided by positive acting pumps. But with the adoption of all of these expedients to raise the liquid film coefficient, the practice has been to use large diameter short tubes or 70 tubes offering such resistance to high velocity flow that only relatively low velocities and 75 heat transfer to the treated liquid has been attained.

It is generally accepted that, when steam 80 or similar heating media are employed, the stagnant film on the outside or steam side of the evaporator tubes is composed of condensed steam and non-condensable gases, such as air, which are always present in or 85 accompany the steam. Although, as will be apparent from the above formula, the steam film coefficient is a factor in the overall rate of heat transfer between the steam side and the liquid side of the tubes, yet under the 90 common practice of employing large diameter tubes and slow circulation of liquid therethrough, the liquid film resistance has been so high that the steam film resistance was, or at least has been considered negligible in the 95 ultimate result. However, by utilizing small diameter long tubes and high velocities such as I propose, the steam film resistance to heat transfer becomes a matter of real importance. Where heating media of the character of flue 100

gases have been used, the heating medium film resistance has been so high that the liquid film resistance was relatively unimportant. Consequently I not only increase 5 the liquid film coefficient by providing high velocity circulation of the liquid through the tubes, but I raise the heating medium film coefficient by reducing the stagnant film of non-condensable gases and condensed vapor on the 10 outside of the tubes.

One of the objects of my invention is to provide an improved method or process of evaporation.

Another object is to provide an improved 15 process or method of operating apparatus for heating liquids to be evaporated.

Another object is to provide a process which will materially raise the liquid film coefficient to increase the overall rate of heat 20 transfer from the heating medium to the treated liquid.

Another object is to provide a process whereby the film coefficient of a heating medium may be raised if desired or necessary 25 still further to raise the overall rate of heat transfer.

Another object is to reduce the formation of scale when evaporating liquids subject to scale formation under heat.

30 Another object is to reduce the formation of foam during the evaporation of liquids subject to foaming.

Another object is to provide a process permitting a reduction of heating area without 35 decreasing but in fact increasing the rate of evaporation.

Other purposes, objects and advantages will appear from the process or method hereinafter described.

40 My improved process or method may be performed by the apparatus shown in the accompanying drawing, but, of course, other apparatus may be employed.

In the drawing:

45 Fig. 1 is an elevation and partial section of an evaporator;

Fig. 2 is an enlarged section on the line 2—2 of Fig. 1, and

50 Fig. 3 is an enlarged vertical section of the top portion of the vertical tube heater on the line 3—3 of Fig. 2.

According to my improved method or process the liquid to be treated is positively forced at a high entrance or initial velocity 55 into an unobstructed substantially straight high velocity zone composed of heating tubes of relatively great length and small diameter. Augmented by the effect of the steam generated during the passage of the liquid 60 through the tubes the velocity of the treated liquid becomes very high, the liquid film coefficient is raised and heat is imparted to the liquid at a rapid rate. The treated liquid is freely expelled or projected from the tubes 65 into the evaporating chamber and, since the

velocity increases as the liquid approaches the exit ends of the tubes, because of the high velocity-accelerating effect of the boiling within the tubes, the liquid film coefficient and rate of heat transfer increase in the direction of expulsion. In order still further to augment evaporation when vaporous heating media such as steam are employed, the heating medium may be caused to flow along the outside of the heating tubes in a direction reverse to that of the treated liquid to remove from the tubes the condensed vapor and non-condensable gases, reducing the film thickness and raising the film coefficient on the heating medium side of the tubes, particularly in the region where the liquid film coefficient is highest.

70 The improved process or method is especially applicable for treating liquids that are viscous, have high boiling points or carry suspended solids, such for example as tar, heavy petroleum, fats and greases, resinous compounds, caustic soda, calcium chloride, salt liquor and various chemical compounds and for use with high temperature heating media.

75 The evaporator chosen for an application of the process has a generally cylindrical metal body 5 which forms a collecting chamber in which separation of vapor and liquid takes place. This body has a cover 6 and a bottom 7. A vapor pipe 8 communicates with this chamber through cover 6. This vapor pipe, as is common in evaporator practice, is for the discharge of vapors driven off during the evaporating process and for the application of whatever vacuum may be desirable.

80 The treated liquid in the evaporator body is heated and boiled in a heating element 9. This heating element comprises, in general, a long tubular section 10 and a relatively short enlarged cylindrical section 11. Tubular section 10 extends below body 5 and projects upwardly through bottom 7 some distance into the evaporating chamber. It is provided with an annular flange 12 by which the heater may be attached to the evaporator body by appropriate means such as bolts 13. A suitable packing ring 14 may be employed to insure a tight joint. Section 10 is tightly closed at its upper end by a tube sheet 15 joined thereto by suitable means such as welding or screws and the like. The lower end of drum section 10 is provided with an annular flange 16 to which the upper flange 17 of the enlarged section 11 is attached by bolts or other suitable means. The lower ends of section 11 has a flange 18 to which a combined bottom plate and lower tube sheet 19 is secured by bolts or the like. This bottom tube sheet is provided with a downwardly extending annular flange 20 for the reception of a liquid inlet pipe to be hereinafter described.

85 A series of long and substantially straight tubes 22, which are open at both ends, extend 120

through the steam drum and openings in the two tube sheets 15 and 19. The ends of these tubes are pressed, expanded or otherwise tightly secured to the tube sheets so that steam 5 under pressure may be supplied to the drum outside of the tubes and cannot escape. In effect, the heater is like a water tube boiler in that the treated liquid is inside of the tubes and the heating medium is on the outside 10 thereof.

Steam is supplied to the drum in the space or chamber around the tubes through a steam inlet 23 controlled by a valve 24. Excessive pressures can be avoided by providing a 15 steam relief valve 25. The enlarged section 11 provides a chamber for the collection and separation of the water of condensation and the non-condensable gases which usually accompany steam. The condensate may be removed by a valved drain 26 located at the 20 bottom of the collecting chamber, while the gases may escape through a valved gas vent pipe 27 at the top thereof. The side wall of section 11 may be made of relatively thin 25 sheet metal so that the additional function of an expansion joint may be performed by this section.

A steam deflector is located within the steam chamber of the drum to direct the flow 20 of steam downwardly along the tubes. This deflector is in the form of a tube 30 which lies between the inner wall of drum section 10 and the group of tubes. Its lower end fits within the inwardly projecting rim 31 of flange 16 and, either by the tightness of the fit or otherwise, forms a closed-bottom steam passage around the tubes. The upper end of steam deflector tube 30 is open and is located somewhat near the upper tube sheet 40 15. Thus, the steam entering the heater through steam inlet 23 flows upwardly in the steam chamber out of contact with the tubes almost to their upper open ends, then flows downwardly in the steam chamber along and 45 in contact with the tubes in a direction opposite to that of the flow of liquid therethrough and finally collects as condensate in section 11. The condensate may be removed through drain 26 and the gases liberated 50 through vent 27. If desired, the lower end of deflector tube 30 may project below flange 16 in order to provide a gas trap in the top of section 11.

Liquid to be treated is supplied by a valved 55 liquid supply pipe 32 in the evaporator body. The liquid is withdrawn from the body through a liquid outlet pipe 33 which leads to a pump 34, such as a centrifugal pump. A valved inlet pipe 35 extends from the discharge side of pump 34 and has its upper end tightly fitted within and connected to flange 20 of bottom plate 19 so that the pump directly and positively forces the withdrawn liquid upwardly into the lower ends of the 60 65 heater tubes.

A somewhat cone-shaped baffle 36 is located above the open ends of tubes 22 in body 5, to disperse and diffuse the hot liquid which is projected from the tubes when the evaporator is in operation. The concentrated liquid, or other products resulting from evaporation, may be withdrawn through a valved outlet 37 in pipe 35. 70

The heating tubes are made relatively long and of small diameter, for example, for ordinary evaporating processes, these tubes may be in the neighborhood of 6 to 10 feet long and $\frac{3}{4}$ to 1 inch inside diameter. The length of the tubes does not excessively increase the height of the evaporator body because the tubes may be largely outside of the body. 75

In operating the evaporator according to my improved method, the liquid which is withdrawn from the evaporator body, is 80 positively pumped directly upward at high velocity into and through the long slender tubes. At the same time, the steam is directed downwardly outside of the tubes, opposite to the direction of the liquid flow 85 therethrough and in the same direction as the force of gravity acting upon the film of condensate and gases which tends to cling to the tubes. Because the steam is directed downwardly by the steam deflector, condensation creates a downward current or flow of the steam along the tubes at a relatively high 90 velocity. The steam velocity is greatest near the upper ends of the heater tubes which is the region where the liquid velocity also is 95 the greatest. Consequently, the steam film coefficient is highest in that region of the heater where the liquid film coefficient is the highest. 100

The entrance velocity of the pumped liquid 105 at the bottom ends of the tubes may, for example, be raised to the neighborhood of 5 to 7 or more feet per second as compared to an entrance velocity probably much less than 1 to 2 feet per second where natural circulation 110 is employed. With this initial high velocity augmented by the lifting effect of the vapor created by the boiling treated liquid, as steam is formed by evaporation while passing through the heating element, attains great 115 speed and momentum as it flows upwardly through the tubes and is projected directly into the vapor space above the level of the liquid in the evaporator body chamber. The high velocity of the liquid flow upwardly 120 through the tubes reduces the stagnant liquid film on the inside of the tubes and also tends to remove and prevent the deposit and collection of scale so that the liquid film coefficient is raised and the scale resistance to heat transfer is reduced. Consequently, the rate 125 of heat transfer and evaporation are high and therefore high liquid velocities are entirely feasible, and excessive pump capacity and power consumption are not required. 130

The downwardly directed and high velocity flow of heating steam carries along the condensate and non-condensable gases which tend to cling as a relatively stagnant and heat transfer resistant film on the outside of the tubes, aiding the force of gravity to carry them to the common collecting and separating chamber at the bottom, where the condensate and gases are removed. Thus, the steam serves to sweep the film from the steam side of the tubes, resulting in a rise of the steam film coefficient and increased heat transfer. And this higher steam coefficient is particularly pronounced in the upper region of the tubes where the liquid film coefficient is likewise highest.

The increase in the rate of heat transfer permits the use of a smaller area of heating surface for the treatment of the same or even greater volumes of treated liquid so that more durable but more expensive metal may be employed for the tubes. Thus, nickel, which for many purposes is by far the most satisfactory metal because of its non-corrosive properties, may be used, although its cost ordinarily has been prohibitive with the prior processes and evaporators because of the relatively large heating surface required.

The extremely high velocity at which the treated liquid and vapors rise through the heating tubes prevents in a large measure the formation and retention of gas bubbles within the body of treated liquid. Further, if such bubbles are formed they are broken by the excessive velocity with which the mass of liquid and vapor, issuing from the tubes, strikes the deflector 36. It is the presence of these gas bubbles which constitutes the principal agent in the formation of foam. Consequently, my high velocity process reduces the tendency to foam, because it reduces or prevents the formation and retention of gas bubbles within the body of liquid, and breaks any foam that may be formed by the action of baffle 36.

By inserting the heating element as a unit from the outside of the body and having all of the connections therefor entirely outside of the evaporating chamber, the placement and removal of the heating element is a relatively easy matter and the number of openings and connections through the wall of the evaporator body is reduced while yet retaining the desirable feature of introducing the steam near the top of the heater. In the event that the heater becomes clogged, or for any other reason requires attention and repair, it may be removed from the evaporator body and a duplicate substituted therefor. Thus, continuous and efficient operation may be insured without duplicating the relatively great expense of providing additional evaporator bodies.

Having described my invention what I

claim as new and desire to secure by Letters Patent of the United States is:—

1. A process of concentrating a liquid by evaporation which includes the steps of setting said liquid in movement at a high velocity in a straight path, leading said liquid in the same direction into and through a heating zone in an unobstructed relatively straight long and narrow path directly into the vapor space of a collecting chamber, and applying to the liquid in its travel through said zone heat in amount sufficient to boil said liquid. 70

2. The process of concentrating a liquid by evaporation which includes, forcing the liquid at high entrance velocity into an unobstructed relatively straight long and narrow high velocity zone, applying to the liquid in said high velocity zone heat in amount sufficient to boil the liquid and thereby augment 80 its velocity, and permitting unobstructed discharge from said high velocity zone directly into the vapor space of a collecting chamber of the liquid and its vapor caused by boiling. 85

3. The method of operating an evaporator having an unobstructed substantially straight and relatively long and narrow tube through which the liquid to be treated passes at high velocity into the vapor space of a collecting chamber, which includes the steps of feeding 95 the liquid at high entrance velocity to the tube, and applying to the exterior of the tube heat in amount sufficient to boil the liquid passing therethrough. 100

4. The method of operating an evaporator having an unobstructed substantially vertical and straight and relatively long and narrow tube through which the liquid to be treated passes at high velocity directly into the vapor space of a collecting chamber, which includes, feeding the liquid at high entrance velocity to the tube, and applying to the exterior of the tube heat in amount sufficient to boil the liquid passing therethrough. 105

5. The method of operating an evaporator having an unobstructed relatively straight long and narrow tube through which the liquid to be treated passes at high velocity directly into the vapor space of a collecting chamber, which includes, feeding the liquid at high entrance velocity to the tube, and applying to the exterior of the tube vaporous heat in amount sufficient to boil the liquid passing therethrough. 115

6. The method of operating a concentrating evaporator, having an unobstructed relatively straight long and narrow tube through which the liquid to be treated flows at high velocity, which includes, feeding the liquid at high entrance velocity into the tube, applying to the exterior of the tube a vaporous heating medium in amount sufficient to boil the liquid in its passage therethrough and thereby progressively raise the liquid film 120 125 130

coefficient toward the discharge end of the tube, the vaporous heating medium being rapidly passed along the tube in a direction reverse to that of the flow of liquid there-
5 through so that the higher heating medium coefficient is in the region of the higher liquid film coefficient, and permitting the liquid and the vapor produced by its boiling to be freely and directly discharged from the tube into
10 the vapor space of a collecting chamber.

7. The method of operating a concentrat-
ing evaporator having unobstructed substan-
tially vertical and straight and relatively
long and narrow tubes for rapidly passing
15 a liquid through a heating zone into the va-
por space of a collecting chamber, which in-
cludes, moving the liquid into the tubes at a
high entrance velocity, and passing along the
outside of the tubes in the heating zone a
20 vaporous heating medium in amount suffi-
cient to boil the liquid in the tubes and there-
by raise the velocity of flow to increase the
liquid film coefficient in the region of the va-
por space of the collecting chamber, the heat-
25 ing medium being passed along the tubes in
a direction reverse to that of the liquid flow
therethrough to raise the heating medium
coefficient in the region of the vapor space
of the collecting chamber.

30 In witness whereof, I hereunto subscribe
my name this 3 day of August, 1927.
